DESIGN FOR A CHAIR

Pierre Bourdelle, New York, N. Y.

Application June 1, 1935, Serial No. 57,089

Term of patent 3½ years

To all whom it may concern:

Be it known that I, Pierre Bourdelle, a citizen of the United States of America and a resident of New York, in the county of New York and State of New York, have invented a new, original, and ornamental Design for a Chair, of which the following is a specification, reference being had to the accompanying drawing, forming part thereof.

In the drawing:

Fig. 2 is a side view of the same.

I claim:

The ornamental design for a chair as shown.

PIERRE BOURDELLE.
